United States Patent Office

Des. 177,207
Patented Mar. 27, 1956

177,207

PICNIC TABLE OR SIMILAR ARTICLE

Ray M. Beller, Aurora, Ill., assignor to Belson Manufacturing Company, North Aurora, Ill., a partnership composed of Harry W. Beller and Frank W. Beller

Application May 23, 1955, Serial No. 36,157

Term of patent 14 years

(Cl. D33—14)

Fig. 3 is a perspective view looking underneath thereof.

I claim:

The ornamental design for a picnic table or similar article, substantially as shown.
